UNITED STATES PATENT OFFICE.

OSCAR T. EARLE, OF NORWALK, CONNECTICUT.

IMPROVEMENT IN HAND-LEVER ATTACHMENTS FOR STEAM-PUMPS.

Specification forming part of Letters Patent No. **142,562**, dated September 9, 1873; application filed March 3, 1873.

To all whom it may concern:

Be it known that I, OSCAR T. EARLE, of Norwalk, in the county of Fairfield and State of Connecticut, have invented certain new and useful Improvements in the Arrangement of Hand-Lever Attachments for Direct-Acting Steam-Pumps, of which the following is a specification:

My invention relates to an improved construction and arrangement of the detachable hand-lever attachments used in direct-acting steam-pumps, for the purpose of operating such pumps by hand in the absence of steam or other motive power usually employed for operating such pumps, and is especially designed to be employed in connection with the steam-pump of this class, for which Letters Patent of the United States have heretofore been granted to me. My invention consists in arranging the hand-lever which works the tappet-arm or piston-rod in a horizontal position, so that a number of persons may be able to work them at the same time.

In the hand-lever attachments heretofore used, the levers have always been placed in a perpendicular position, which renders it impossible for more than one man, or two, at least, to operate said levers at one time. This position has rendered such attachments ineffective when applied to large engines, and, in most cases, when applied to smaller ones.

The object of my invention, therefore, is to overcome these defects, and to construct a detachable hand-lever attachment that will allow almost any amount of hand-power to be applied to such pumps. It has been found, also, in the cases of such pumps with perpendicular hand-lever attachments, that it is in

most cases necessary to erect platforms over the pumps, in order that the operative may reach such levers, which is not only an expensive, but an exceedingly clumsy and inconvenient arrangement.

In the drawings, Figure 1 represents a view looking down upon the steam-pump, and showing three different ways in which the levers may be applied.

A, B, and C represent the levers, extending horizontally across the piston-rod and bed of the pump and engine, the levers A, B embracing the tappet-arm D by means of a yoke or open slot in the end, as in A, or near the center, as in B, the lever C passing through a horizontal slot in the tappet-arm E, and all having fulcrums on a brace or support, F, extending from either side of the pump between the two cylinders. In each case the lever is attached at its fulcrum by means of a removable pin, or otherwise, in such a manner that it may be readily detached.

It will be seen that the lever, as arranged, may be readily reached in each case without the employment of platforms, and that any number of men may work upon them at the same time, the number being only limited by the length of the levers.

What I claim is—

The combination of the detachable hand-lever for direct-acting steam-pumps, arranged horizontally between the two cylinders, and the tappet-arm, substantially as described.

OSCAR T. EARLE.
